DIE STOCK AND TAP WRENCH

Herbert J. Smith, Greenfield, Mass.

Application December 3, 1937, Serial No. 177,956

10 Claims. (Cl. 10—123)

This invention relates to improvements in die stocks and tap wrenches, and is directed particularly to a combined holder for removably securing and supporting a die and tap, preferably, but not necessarily, complementary to each other.

An object of this invention is to provide, in a single stock or holder, means for removably securing and supporting a die and tap, whereby either the die or tap may be used without either

10 interfering with the operation of the other.

Another object of this invention is to provide a simple, efficient, combined die stock and tap wrench which is extremely economical of manufacture, and thereby available to the public at

15 an attractive price.

A further object of this invention is to provide, in a combined die stock and tap wrench of the character described, means for removably securing a die and tap in operative positions, and

20 cooperating means for locking the die in operating position and for securing the tap against rotation in the holder.

These, and other objects and advantages of this invention will be more completely disclosed

25 and described in the following specification, the accompanying drawing, and the appended claims.

Broadly, this invention comprises a die stock provided with the usual oppositely disposed handle portions and formed with a socket for removably

30 securing and supporting a die therein, a spring sleeve or quill secured in the die stock and provided with a square socket for receiving the square shank of a tap, a locking screw for securing the die in the socket and for securing the

35 die and quill against rotation, the die stock being provided with means for centering and supporting the die stock on the dead center of a lathe or similar mechanism with the axis of the quill on the axis of the dead center.

40 A preferred form of this invention is illustrated in the accompanying drawing, in which:

Fig. 1 is a side elevational view of the assembled die stock and tap wrench, with die and tap in place therein.

45 Fig. 2 is an enlarged view, similar to Fig. 1, partially in section, illustrating the securing means for the die and quill.

Fig. 3 is a sectional view taken on the line 3—3 of Fig. 2.

50 Fig. 4 is a sectional view taken on the line 4—4 of Fig. 2, and

Fig. 5 is a view similar to Fig. 1, partially in section, illustrating a modified form of holder for use with adjustable dies.

55 Referring now to the drawing in detail, in

which like numerals refer to like parts throughout:

A die stock 1 is formed with a body portion 2 and oppositely disposed handle portions 3. The body portion 2 is formed with a shouldered socket 4 for receiving a die 5, and a boss 6 which is provided with a bore 7 for receiving a quill or sleeve 8, the axis of the bore 7 being perpendicular to the axis of the die-receiving socket 4.

The quill or sleeve 8 is provided with a bore 9 for receiving the round shank 10 of a tap 11, the bore 9 terminating in a square socket 12 for receiving the square end 13 of the shank portion 10. The portion of the quill 8, having the bore 9, is provided with one or more slots 14 to provide a spring grip on the shank 10. The quill 8 is preferably pressed into the body portion 2 of the die stock 1, and is preferably considered a permanent part of the die stock 1, although it may be removed if desired, for repair, replacement, or other purposes.

With the quill 8 in place, the boss 6 is drilled and tapped to receive a setscrew 15 in such a manner as to penetrate the wall of the quill 8, as best shown in Figs. 2 and 4, so that engagement of the screw 15 in the wall of the quill 8 will securely lock the quill 8 in place and prevent its rotation. The screw 15 is preferably provided with a cone point 16 which engages a complementary countersink 17 in the side of the die 5 to secure the die 5 in the socket 4 and prevent rotation of the die 5 relative to the holder 1.

The body portion 2 of the stock 1 is formed with a boss 18 opposite the boss 6, and the boss 18 is provided with an opening 19 for receiving the dead center point of a lathe or similar mechanism. The axis of the opening 19 is identical with the axis of the quill 8, so that, with work held in a chuck or face plate of a lathe, the die stock may be securely held and guided by the dead or tail center of the lathe with the axis of the tap 11 in true registration and alignment with the axis of the hole in the work to be tapped.

In the modified form of stock illustrated in Fig. 5, additional screws 20, located on either side of the screw 15, provide means for adjusting the split die 5' in the socket 4.

The tap 11 is securely gripped in the spring quill 8, and engagement of the square shank 13 in the square opening 12 prevents rotation of the tap 11 relative to the quill 8 and stock. However, the tap 11 may be removed from and inserted in the quill 8 without disturbing the locking screw 55

15, which engages the quill 8 but does not engage the tap 10.

It will thus be understood that I have provided a combined die stock and tap wrench in which 5 a die and tap, preferably complementary to each other, may be removably secured in operative position, and locked in such position against movement relative to the holder by a single locking element.

10 Whereas, I have disclosed and described a preferred form of this invention, it will be understood by those skilled in the art that minor 15 changes in the proportions, shape, and construction of this device may be made without departing from the scope of the invention, and therefore, I do not limit myself to the exact form disclosed.

What I claim is:

1. In a die and tap holder, a body portion provided with a socket for receiving a die, a spring 20 sleeve in said body portion for receiving a tap and having an axis angularly disposed to the axis of said socket, and a single locking element for locking a die in said socket and for locking said sleeve against rotation relative to said body 25 portion.

2. A die and tap holder comprising a substantially circular body portion having flat, parallel side faces and provided with oppositely disposed handle portions and a central shouldered socket 30 for receiving a die, the axis of said socket being perpendicular to said side faces, said body portion being also formed with a bore having a radial axis and communicating between the perimeter of said body portion and said socket, a spring 35 quill secured in said bore for receiving a tap, and a locking element in said body portion engaging said quill and a die in said socket for locking said quill and said die against rotation relative to said body portion.

3. A die and tap holder comprising a substantially circular body portion provided with oppositely disposed handle portions and a central bore for receiving a die, a boss on the perimeter of said body portion provided with a radial bore, a 45 quill secured in said radial bore for receiving a tap, and a setscrew radially disposed in said body portion and engaging said quill and a die in said central bore—for locking said quill and said die in said holder.

4. A die and tap holder comprising a substantially circular body portion provided with oppositely disposed handle portions and a central bore for receiving a die, a boss on the perimeter of said body portion provided with a radial bore, a 55 quill secured in said radial bore for receiving a tap, and a setscrew radially disposed in said body portion and engaging said quill and a die in said central bore—for locking said quill and said die in said holder, said body portion being also provided with a radial socket opposite said radial bore and on the same axis therewith for receiving a dead center point of a lathe tail stock or similar mechanism for guiding a tap secured in said quill.

5. A tap wrench comprising a substantially circular body portion provided with oppositely disposed handles and an axial bore, said body portion being also formed with a radial bore having an axis substantially perpendicular to the 70 axis of said handles, a quill for receiving a tap

removably secured in said radial bore, a locking element radially disposed in said body portion and engaging said quill for locking said quill in said body portion.

6. A tap wrench comprising a substantially circular body portion provided with oppositely disposed handles and an axial bore, said body portion being also formed with a radial bore having an axis substantially perpendicular to the axis of said handles, a quill for receiving a tap 10 removably secured in said radial bore, a locking element radially disposed in said body portion and engaging said quill for locking said quill in said body portion, said body portion being provided with a radial socket opposite said radial bore and on the same axis therewith for receiving a guiding element for a tap secured in said quill. 15

7. A tap wrench comprising a substantially circular body portion provided with oppositely disposed handles and an axial bore, said body portion being formed with a radial bore, a spring quill for receiving a tap secured in said radial bore and extending outwardly therefrom, said quill being provided with a cylindrical opening 20 for receiving the shank of a tap and a square opening communicating with said cylindrical opening for receiving the square end of a tap shank, a locking element radially disposed in said body portion and engaging said quill. 25

8. A tap wrench comprising a substantially circular body portion provided with an axial bore and a radial bore, a quill secured in said radial bore and projecting therefrom, the projecting portion of said quill being slotted to give a spring 30 effect, said quill being formed with a circular opening for receiving the circular shank of a tap and a square opening communicating with said circular opening for receiving the square end of a tap shank, a locking element radially disposed in said body portion and engaging said quill and projecting into said axial bore, said body portion being formed with a radial socket opposite said radial bore and on the same axis therewith for receiving a guiding element for a 35 tap in said quill. 40

9. In a combined die stock and tap wrench, a substantially circular body portion, provided with an axial opening, a spring quill secured in said body portion and having a radial axis, said body portion being formed with a radial socket opposite said spring quill and on the same axis for receiving a guiding element for a tap 45 secured in said quill. 50

10. A combined die stock and tap wrench comprising a substantially circular body portion provided with a central socket for receiving a die and a radial bore communicating with said central socket, a sleeve secured in said radial bore and provided with an axial opening for receiving a tap, said body portion being provided with a radial socket opposite said radial bore and on the same axis therewith, a plurality of set-screws radially disposed in said body portion for adjustably securing an adjustable die in said central socket, one of said screws engaging said sleeve for locking said sleeve against rotation in said body portion. 55 60 65
